INVENTOR.

BY John W. Spellman
ATTORNEY

UNITED STATES PATENT OFFICE.

OSCAR P. McGEE, OF DALLAS, TEXAS.

ELEVATOR-DOOR HANGER.

Application filed June 11, 1921. Serial No. 476,793.

To all whom it may concern:

Be it known that I, OSCAR P. McGEE, a citizen of the United States, residing at Dallas, in the county of Dallas and State of Texas, have invented certain new and useful Improvements in Elevator-Door Hangers, of which the following is a specification.

This invention relates to elevator doors and pertains more particularly to an improved hanger for elevator doors and to the special and improved arrangement and construction thereof.

It is the principal object of the invention to provide an elevator door hanger which will allow of the free and easy movement of the elevator doors, simply arranged and constructed and particularly designed so that the friction in its parts will be greatly reduced and where the wear consequent to such friction present will be uniform, obviating rough, uneven rolling surfaces such as is usually the case, and further providing a true and level path upon which the hanger rollers may travel in carrying the elevator doors.

Other minor but important features will become apparent and obvious by reference to the following description, taken in connection with the accompanying drawing forming part hereof, in which—

Figure 1 is an inside elevation of a set of elevator doors, partly broken away, embodying my invention, and showing the doors suspended upon the improved hangers.

Figure 2 is a top view of the hangers removed from the elevator opening or shaft.

Figure 3 is an enlarged cross-sectional view of the hangers taken on line 3—3 of Figure 4, and

Figure 4 is an enlarged side elevational view of the hangers with part broken away.

Referring more particularly to the drawings, 1 denotes the side walls of an elevator well or shaft, and 2 and 3 the elevator doors proper, 4 representing a stationary or fixed door.

The hangers have a frame work consisting of a longitudinal back plate 5 by means of which the hangers are secured in position between adjacent side walls 1—1, see Figure 3, of the elevator shaft. Secured to the back plate 5 by means of the right-angled braces 6—6 and bolts 7—7 is an angle bar 8 which

parallels the back plate 5 about two-thirds of its distance or length, see Figure 2, and which bar 8 carries a grooved lower trackway 9, the same length as the bar 8, the trackway 9 being bolted as at 10 to the angle bar 8. A plurality of roller bearings 11—11 properly spaced apart and connected by metallic strips 12—12 are arranged to roll in the trackway 9 and a hanger plate 13 to which the doors are attached by means of the bolts 14—14, carries a grooved upper member 15. The roller bearings 11—11 being properly spaced apart and connected by the strips 12—12 permit the member 15 to move easily and securely in the trackway 9. The bottom of the trackway 9 has a rib or rail 16 and each of the hanger plates 13 has a roller 18 set therein, the rollers riding against the under side of the trackway. By this latter arrangement the hanger plates are prevented from moving laterally and thus their dislodgement from the trackway is prevented.

The elevator doors may be hung with door 3 slightly in advance of the door 2 upon a trackway extending the entire length of the back plate 5, the angle bar supporting which trackway being shown on the drawing, Figure 2, as 8^a. This trackway, with the exception of its greater length, is in all parts identical with the trackway upon which the door 2 travels.

A bumper 19 is also provided at the end of the trackways 9 to lessen vibration and jar.

What is claimed is—

A hanger for suspending elevator doors, comprising a back or base plate, angle plates spaced apart longitudinally thereof and connected to the back plate; parallel grooved trackways spaced apart and suspended from the angle plates; a longitudinally projecting rail on the underside of said suspended trackways; hanger plates carrying doors and having plates vertically extending above the suspended trackways; a plurality of roller bearings spaced apart and disposed between said suspended trackways and said upper trackways and grooved rollers carried by the hangers and adapted to ride against said longitudinally projecting under rail.

In testimony whereof I have signed my name to this specification.

OSCAR P. McGEE.
